UNITED STATES PATENT OFFICE

WILLIAM H. JOHNSEN, OF DALLAS, TEXAS

CHEMICAL CARBON REMOVER

No Drawing.

Application filed July 3, 1930. Serial No. 465,791.

This invention relates to a composition of matter for removing the carbon deposits which are more or less rapidly formed in the combustion chambers of the cylinders of internal combustion engines, around the valves, upon the spark plugs, and also upon the heads of the pistons, which deposits seriously interfere with the efficient operation of the engine.

The invention has to do particularly with the compounding of a liquid chemical carbon remover, which may be introduced into the cylinders of the engine through an attachment placed on the intake manifold, or injected through the spark plug openings of the engine.

When the composition of this invention is introduced in either of the manners above suggested, the engine may be run for a few seconds to bring the composition in contact with the carbon deposits, whereupon the engine is shut off and allowed to remain idle for a certain period. During this time, the composition will soften the carbon formed on the engine parts so that, as soon as the engine is again started, the loosened particles of carbon will be discharged through the exhaust.

It has been found that a suitable mixture embodying this invention may be made with various ingredients added in quantities, substantially as follows:

	Per cent
Isopropyl-ether	20
Acetone	20
Propylene-di-chloride	20
Ethylene-di-chloride	20
Chlorinated naphthalene	20

It is to be understood that the composition may be varied by changing the proportions or by eliminating one or more of the specified ingredients. For example, it has been found that a satisfactory carbon-removing composition may be made by leaving out either the ethylene-di-chloride or the propylene-di-chloride and increasing the proportions of the remaining chemicals.

By way of an example of one method of carrying out this invention, it has been found

that, for one cleaning operation, approximately six fluid ounces of the composition are sufficient to remove the usual carbon deposits, but it will be understood that a larger quantity may be employed without injuring in any way the metal parts or interfering with the operation of the engine.

What is claimed is:

1. A composition of matter for removing carbon deposits from internal combustion engines, comprising substantially equal proportions of isopropyl-ether, acetone, propylene-dichloride, ethylene-dichloride and chlorinated naphthalene.

2. A composition of matter for removing carbon deposits from internal combustion engines, comprising substantially equal proportions of isopropyl-ether, acetone, propylene-dichloride and chlorinated naphthalene.

3. A composition of matter for removing carbon deposits from internal combustion engines, comprising substantially equal proportions of isopropyl ether, acetone, ethylene-di-chloride and chlorinated naphthalene.
